UNITED STATES PATENT OFFICE.

WILLIAM S. DUNHAM, OF SHARPSVILLE, PENNSYLVANIA, ASSIGNOR OF ONE-HALF TO
WELLS WHEELER, OF SHARPSVILLE, PENNSYLVANIA.

SYSTEM OF HANDLING GRANULAR SLAG.

1,282,781.

Specification of Letters Patent. Patented Oct. 29, 1918.

Application filed November 21, 1917. Serial No. 203,252.

To all whom it may concern:

Be it known that I, WILLIAM S. DUNHAM, a resident of Sharpsville, in the county of Mercer and State of Pennsylvania, have invented a new and useful Improvement in Systems of Handling Granular Slag, of which the following is a specification.

This invention relates to apparatus for handling fine material, and particularly 10 granular slag.

The object of the invention is to provide means for carrying granular waste material from a hopper car to a distance from a railway track, and there to discharge it. The 15 apparatus for accomplishing this object, and other objects which will more fully appear, comprises a trough adapted to receive material when discharged from the bottom of an ordinary hopper car, and to carry it by 20 force of a stream of water through a series of connecting troughs to any desired discharge point. Means are provided for producing the necessary water pressure, and for applying this at any desired point.

Referring to the drawings, Figure 1 is a 25 side elevation showing the complete invention, in use with one form of hopper car; Fig. 2 is a longitudinal central section through the discharge trough of the apparatus, on an enlarged scale; Fig. 3 is a cross section on the line 3—3 of Fig. 1; Fig. 4 is a partial section and end view of the trough, on the line 4—4 of Fig. 2; Fig. 5 is a vertical section showing a modification, 30 adapting the apparatus to a different type of car, the trough being located underneath the railway track; and Fig. 6 is a plan view showing another modification adapted for use with a type of car having longitudinal 35 central or side discharge openings.

In handling certain materials, such as 40 granular slag, it is frequently desirable to transport them in railway hopper cars and to discharge them therefrom on either a waste bank, or dump, or else to use this material for filling waste grounds or building 45 up the sides of railway grade banks. Unless the material is discharged directly from the bottom of the car, and allowed to fall 50 through a trestle support, it must be removed from the car by external means, such as hauling in wagons, wheel barrows, etc. It is very desirable for the purpose of economy of labor and time that such material 55 be transported directly to the point where

it is to be dumped, and that the discharge may be made directly and automatically from the car to the point where the material is to remain. The present invention furnishes means for accomplishing this object. 60

Ordinarily slag is used for filling low ground, or at any rate it is discharged in such manner that tracks may be laid on the bank of dumped material, to support cars 65 which transport it to the dump. By the methods usually employed, it is necessary to frequently relay the tracks to keep them at the edge of the pile of loose material.

The apparatus of this invention comprises 70 a connection 1 to any suitable source of water supply,—here shown as a pool or stream W,—a pump of any desired form, as for example a centrifugal pump 2, driven by direct connection to a motor 3. The 75 pump has a connection 4 to a main 5, which extends nearby and parallel to the rails 6 of a track laid along the top of the bank formed by dumping the granular material. The main 5 has at intervals of about a car 80 length apart, hydrants 7, adapted to be connected to a hose 8, and controlled by hand operated valves 9.

A trough 10 is adapted to extend across the track and to seat on the rails thereof, as 85 shown in Fig. 1. This trough is entirely open at the top and at one end. The other end is closed by a wall 11, through which extends a circular casing 12, as shown in section in Fig. 2. Fixed on the outside of 90 the wall 11, is a windlass 13 having a ratchet wheel 14 and pawl 15 connected so as to normally allow the windlass to turn in one direction only. The windlass is driven by a shaft extension 16, and crank 17. 95

The casing 12 is adapted to receive a metal pipe nozzle 18, clamped in the end of hose 8. The nozzle may be freely moved back and forth inside the casing 12.

By means of the windlass just described, 100 the nozzle may be forced into the trough against a considerable back pressure, as and for the purposes more fully described below.

Troughs 19 are provided to extend from the main trough 10, to any desired length. 105 These latter units are in the form of troughs similar in cross section to that of the main trough 10, but open at each end and unobstructed throughout their length. Any desired number of these units may be connect- 110

ed up in the manner shown in Fig. 3, by simply lapping each trough over the next succeeding trough, and preferably applying them to a surface which will furnish a slight 5 inclination toward the open end.

The operation of the apparatus is as follows:

One or more cars loaded with slag, or similar granular material, which it is desired to dump on the edge of bank 20, are transported to the desired position on the tracks. By reason of the position of water main 5 alongside this track, for a considerable distance, and the provision of connections 10 7 at frequent intervals along the main, cars may be unloaded at any position that they may be left. For example in Fig. 1, the steel hopper car 21 is not exactly beside one of the hydrants 7, but the connecting 15 hose 8 is of such length that it extends to the car. If the position of the car were different, the only result would be the necessity of connecting the hose to a different hydrant. The car 21 is a standard form of steel hopper car, having transverse discharge gates. The trough 10 is placed directly beneath these gates, and supplementary troughs 19 are connected, extending to the edge of the bank 20. The trough 10 is held in place by 20 a track hook 22, as shown in Fig. 3. Water driven under considerable pressure by the pump 2 is forced through the nozzle 18, and discharged through the series of troughs. This stream having been previously established, the gate 23 of the car is opened, allowing granular slag, or other waste material, to run from the car into trough 10. The fine material is carried off by the stream 25 of water from the nozzle 18 and transported along the troughs 19 to the edge of the bank as shown in Fig. 3. There the water readily soaks into the bank or runs away, leaving the granular material deposited just as though it had been dumped directly from the car on the edge of the bank.

There is a considerable back pressure on the nozzle 18, which is the reason for having the ratchet attachment on the windlass 13 as above described. By this arrangement and 30 by the connecting rope 24, attached at one end of the windlass and at the other to a collar 25, on the nozzle 18, the nozzle is not only held in place against reverse pressure, but may be forced to any desired position 35 against pressure underneath the load of slag dumped into the trough from the discharge openings of the car.

The car 21 has transverse gates 23, connected by a cross bar 26, as shown in Figs. 1 40 and 3. With this type of car, the material is discharged directly into the trough 10 which may be placed on top of the rails, without any other attachment than hook 22. However, a number of different types of hopper 45 cars are standard equipment, and it may be

necessary to modify my trough arrangement somewhat in order to take the direct discharge of the material from various types of hopper cars.

In Figs. 5 and 6 are illustrated diagrammatically, a different car body, and means for receiving the discharge therefrom. In Fig. 5, a car body 21^a is illustrated, the trucks being omitted for the sake of clearness. This type of car has longitudinal discharge openings, which would normally throw the dumped material outside the track, or in the middle thereof. In Fig. 6, I have shown means for receiving discharge from such cars, as well as from any type in which there is a central longitudinal discharge opening, or longitudinal side openings. This arrangement consists in putting the main receiving trough 10 underneath the rails, and across the track and providing supplemental longitudinal receiving troughs, or hoppers 27, and 28. The hoppers 27 are situated just outside the track and parallel thereto and are somewhat greater in length than the car discharge opening from which they are adapted to receive material. The hopper 28 is situated between the rails and is adapted to receive material from a central longitudinal opening as will be obvious. Each of these supplemental hoppers, 27 and 28 has sloping sides and has a central opening at the bottom, adapted to discharge material into the trough 10, from which it is carried off as described in connection with Figs. 1 and 3, above. Other modifications 50 may be provided to take care of special forms of discharge openings, as will be obvious.

During the unloading operation the nozzle 18 may be moved back and forth, according 55 to the requirements of the special case, and it will be found that the granular material will be carried down the trough by force of the stream of water and discharged at the desired point.

It will be understood that the apparatus is applicable to other materials than slag, such as sand, coal dust, waste dust, etc.

I claim:

1. Apparatus for discharging granular material from hopper cars comprising a trough extending across the track beneath the discharge port of the car, a nozzle extending through a closed end of the trough, means fixed on the trough to adjust the position of the nozzle relative to the discharge port of the car, means to force a stream of water under pressure through the nozzle whereby to carry the granular material from the opening end of the trough, and a series of separable extension members adapted to lead the discharged material from the end of the trough.

2. Apparatus for discharging fine material from hopper cars comprising a trough

- extending across a track beneath the discharge opening of the cars, said trough having one end closed and the other open, a casing in the end of the trough, a pipe extending through the casing fixed in the closed end of the trough, a windlass on the closed end of the trough, a rope attached to the outer end of the pipe and to the windlass whereby to adjust the position of the 5 nozzle relative to the discharge opening of the car, and means to force a stream of water under pressure through the pipe to carry off the material in the car into the trough.
- 10 3. Apparatus for discharging powdered material from hopper cars comprising a source of water pressure, a water main ex-
- tending parallel to a railway track, connection at car lengths to said water main, a trough adapted to extend across the track 20 beneath the discharge opening of the car on the track, a hose connected to the water main, a nozzle on the hose extending into the trough and supported thereby, means to force the nozzle forward relative to the 25 length of the trough, and separable extensions of the trough whereby the powdered material is carried to a discharge point at a distance from the track.
- 15 In testimony whereof, I have hereunto set 30 my hand.

WILLIAM S. DUNHAM.
